UNITED STATES PATENT OFFICE

1,997,348

OIL BURNER APPARATUS

Oscar C. Schroeder and Stanley Perry, Chicago,
Ill.; said Perry assignor to Automatic Burner
Corporation, Chicago, Ill., a corporation of
Illinois

Original application October 26, 1932, Serial No.
639,685. Divided and this application April 3,
1933, Serial No. 664,217

1 Claim. (Cl. 158—86)

Our invention relates to oil burner structures of the type comprising upwardly extending shells, commonly of cylindrical form and spaced apart, certain thereof being perforated, and forming between them a combustion chamber and more especially, though not exclusively, to burners of the type referred to in which wicks are located at the bottoms of the combustion chambers for absorbing oil supplied thereto and which is ignited at the wicks by the operator for the pre-heating of the burners; the type of burners to which this invention more particularly relates being the type which are located in the fire pots of ranges, stoves, or the like, and are commonly referred to as range burners, the subject matter of the present application constituting a division of our application for United States Letters Patent Serial No. 639,685, filed October 26, 1932.

Heretofore the constructions of burner apparatus of this type and employing wicks have been such that the lighting of the wicks is effected by the introduction of a torch or taper downwardly through the top of the burner structure, which is not only an awkward way of lighting the burner but is often inconvenient and often results in objectionable displacement of parts of the burner and is generally regarded in practice as an objection much desired to be overcome, this objection being more pronounced in stoves, ranges, or the like, without cover lids, and requiring the use of a torch or taper, for the lighting of the wicks, which is introduced downwardly into the combustion chamber through a door in the side of the stove or range.

One of our objects is to provide for the simple and easy lighting of the wicks of oil burners especially when installed in stoves, ranges, or the like, and without requiring the introduction of the lighting element into the combustion chambers through their tops and without disturbing the shells or cover plates at the tops thereof when formed of separate parts.

Another object is to provide improvements in burner structures to the end that the burner will become quickly conditioned, after lighting, for normal functioning.

Another object is to accomplish such quick conditioning of the burner for normal functioning in the case of a burner formed of a plurality of combustion chambers located one within the other; and other objects as will be manifest from the following description.

Referring to the accompanying drawings:

Figure 1 is a view in front elevation of an oil burner embodying my invention showing it in-

stalled in a stove illustrated in vertical sectional elevation.

Figure 2 is a broken section taken at the line 2 on Fig. 1 and viewed in the direction of the arrow, the burner being shown in side elevation.

Figure 3 is an enlarged fragmentary sectional view of one of the similar burners, the section being taken at the line 3 on Fig. 1 and viewed in the direction of the arrow.

Figure 4 is a broken view in elevation of a burner showing another embodiment of the invention.

Figure 5 is a plan view of the burner assembly of Figs. 1 and 2.

Figure 6 is a plan view of one of the similar burner heads of Fig. 5 with certain parts removed.

Figure 7 is an enlarged broken sectional view taken at the line 7 on Fig. 5 and viewed in the direction of the arrow.

Figure 8 is an enlarged broken sectional view taken at the line 8 on Fig. 5 and viewed in the direction of the arrow.

Figure 9 is an enlarged plan view showing a modification of the burner assembly; and

Figure 10, an enlarged broken developed sectional view taken at the line 10 on Fig. 6 and viewed in the direction of the arrow.

Referring to the construction shown in Figs. 1, 2, 3, 5, 6, 7, 8 and 10, 11 represents, by way of example, a range generally of common construction and presenting an elongated fire pot 12 extending lengthwise across one end of the range and an oven 13 at the other end thereof, the outer side wall of the fire pot 12 which extends across the adjacent end of the range having an opening 14 controlled by a door 15 hingedly supported at its lower edge as represented at 16 and shown as provided with a substantially vertical baffle plate 17 extending into the opening 14.

Located in the fire pot 12 is an oil burner embodying my invention and shown as comprising two oil burner heads 18 alike in construction and which extend in a series lengthwise of the fire pot 12.

The burner heads are shown as supported on a plate 19 which, in turn, is supported at legs 20 on the bottom 21 of the fire pot, the arrangement being such that the burner heads 18 extend substantially in the horizontal plane of the opening 15.

The burner heads 18 are shown as supplied with fuel at the rear thereof (viewing the structure as in Fig. 1). The oil may be supplied to the burner heads in any desirable way and under

any suitable control, as for example as is commonly provided for in oil burning apparatus, and to limit the depth of oil which may accumulate in the burner and as hereinafter referred to, the oil supplying means shown for this purpose comprising piping 22 which would connect with any suitable source of fuel-oil supply regulable to prevent overflow to the burner as above stated, and presenting terminal outlet pipes 23 which open into the rear portions of the burner heads 18.

The particular burner heads 18 illustrated are of the same general construction as the burner heads shown and described in our pending application for United States Letters Patent Serial No. 497,814, filed November 21, 1930, each involving a base ring 24 having upturned flanges 25 and 26 at its inner and outer peripheries, with its base portion upwardly deflected as represented at 27, except at the zone represented at 28 at which the oil feed pipe discharges upwardly into the burner head, a ring 29 having depending annular flanges 30 and 31 apertured at intervals along their lower edges and superposing the deflected portion 27 and with which latter and the flanges 25 and 26 forming troughs shown as containing annular wicks 32 and 33, and four perforated cylindrical shells 34, 35, 36 and 37 extending one within the other and spaced apart and telescoped with the flanges 25 and 26 and the flanges 30 and 31 of the ring 29, the shells 34 and 35 forming the side walls of an inner combustion chamber 38 and the shells 36 and 37 forming the side walls of an outer combustion chamber 39, the annular space between the shells 35 and 36 opening at its lower end to the atmosphere through an annular series of pipes one of which is represented at 40, whereby combustion-supporting air is supplied through the shells 35 and 36 to the combustion chambers 38 and 39.

A cover plate represented at 41 extends over the annular chamber formed by the shells 35 and 36 and the combustion chamber 38 and is apertured as represented at 42 to render the top of the chamber 38 open.

The burner shown is started into operation by the operator igniting the oil on the outer wicks 33 and supplied thereto through the pipes 23, the apparatus, to the end of permitting of the easy and ready lighting of the wicks, involving the provision of an opening 43 in the front side of each shell 37 adjacent its lower edge and thus substantially in line with the upper edge of the wicks 33 through which the operator, reaching through the opening 14 in the fire pot wall (assuming the door 15 to have been previously opened) inserts a match, or other suitable lighting means, for igniting the oil on the wick.

As will be understood, should the fuel used be highly volatile the wicks may be dispensed with, in which case the fuel would be ignited by igniting the vapor rising therefrom by any suitable lighting means introduced through the opening 43.

The opening 43 is provided with a closure shown as in the form of a door 44, there being preferably interposed between the door 44 and the shell 37 a tubular casing 45 secured to the shell 37 and to which the door 44 is hinged at its upper edge as represented at 46, the hinge 46 being positioned at such a distance from the shell 37 that in the swinging of the door 44 upwardly to open position it moves beyond dead center and thus remains in open position until swung by the operator out of this position.

According to the embodiment of the invention illustrated in Fig. 4, the removable closure member for the opening 43, instead of being in the form of a hinged plate as in Figs. 1-3, is in the form of a slide which is represented at 47 and slides at its opposite vertical edges in vertical guides formed by angle plates 48 secured to the outer surface of the shell 37, the closure member 47 being provided with a projection 49 to be engaged by the hand of the operator to facilitate the opening and closing thereof.

Where the burner heads are of such construction or size as to render it necessary or advisable to introduce the oil into the base member of the burner at a plurality of points (in which construction a flat zone, such as that shown at 28 in Figs. 6 and 7, would be provided in each burner head base at each oil inlet to permit flow of oil to all base of the wick troughs) the parts of the apparatus would be so positioned that the closure-equipped opening in each outer shell and corresponding with the openings 43 of Figs. 3 and 4, would be located midway between adjacent ones of the oil-inlets of each burner head. Thus, by way of example and as shown in Fig. 9, where two oil inlets for each burner head and shown at 50 are provided in diametrically opposed position, the closure-equipped opening for each burner head would be located midway between the inlets 50.

It may be here stated that the purpose of providing the opening 43 at a point diametrically opposed to the single oil inlet as in the case of the construction shown in Figs. 1, 2 and 5, and midway between the oil inlets of a burner head where two such inlets are provided, as in the case of the construction shown in Fig. 9, is to provide for the igniting of the fuel at a point as far remote as possible from the oil inlet, or oil inlets, as the case may be, thereby insuring the rapid propagation of the flame throughout the circumference of the combustion chamber and the rapid establishment of uniform combustion conditions throughout the circumference of the burner and which is of particular importance in constructions employing wicks as above described.

In the starting of the burner, wherein the ignition flame is applied to the outer wick at the farthest point from the oil inlet, the application of the heat by the ignition flame to the outer wick opposite the oil inlet tends to draw the first vapors produced to that point allowing that portion of the outer burner element (which contains less oil) to be preheated sufficiently in advance of the oil inlet portion to overcome the tendency of the burner to develop more heat near the oil inlet side due to the greater amount of oil contained at that point. In other words, the application of heat at the point referred to establishes a draft which draws more vapor to the side of the outer burner element where the least amount of oil is present, as the flame travels around the outer wick. This makes up for the lesser amount of oil on this side, causes the outer burner ring to be heated more uniformly and in advance of the inner burner ring and balances the outer ring, insuring equal distribution of the flame around it.

By the time the flame is fully established around the outer wick, which requires approximately two minutes, the oil in the vapor chamber 28 has become heated and the flame from the outer wick flashes across to the inner burner element which, being uniformly heated around its entire circumference, ignites almost instantaneously and in approximately two more minutes

has acquired a degree of temperature comparable to the outer burner element and complete balance is reached. In a few more minutes the perforated shells show full red and in from five to ten minutes after lighting the burner is in full operation. Furthermore, it has been found practicable to open the oil valve to normal position, ignite the outer wick as described, and leave the burner without further attention, a procedure not practical with other types of equipment.

Contrasted with the operation of the burner as above described is the operation of a burner in which the burner is lighted by first lighting the inner wick, or lighting the burner at a point adjacent the oil inlet. If the inner wick is lighted first there is a tendency of all of the vapors generated to be drawn to the center of the burner thereby delaying the establishment of normal combustion conditions in the outer burner ring. Where the wick is ignited at the oil inlet there is a tendency, due to the extra quantity of oil at the oil inlet, both when priming and during the oil flow to replace that which has been burned, to overheat the burner at this point when first lighted and the incoming oil to continue to burn at this point as in the case where the inner burner element is lighted first, this condition being possibly worse than the first as the heat is concentrated at one point, namely, at the oil inlet. While the burner may eventually reach a balance it is generally necessary to "flood" the burner with oil to overcome this condition.

In either case, namely, lighting the inner wick first or lighting the burner at the oil inlet, it requires from 20 to 25 minutes for full generation of the burner as compared with the relatively short time required where the burner is constructed in accordance with my invention and operated as above described.

The oil supplying means is preferably adjusted to prevent the oil supplied to the burner from rising to a height sufficient to fill the space 28 which connects the two combustion chambers 38 and 39. The oil at the bottom of the outer combustion chamber 39 having become ignited, the oil in the space 28 becomes vaporized with the result that by reason of the propagation of the flame across the space 28 the oil at the in-

ner wick 32 becomes ignited, the lighting of the inner wick 32 from the outer wick 33 quickly occurring upon lighting the outer wick, due to the wide passage connecting the inner and outer combustion chambers at 28 and which lends itself to the ready propagation of the flame across this passage to the inner wick.

The claim of this application is not directed to any feature of the burner structure independent of the provision of a lighter opening in the outer side wall of the burner, as the novel features of the burner construction, regardless of the provision of the lighter opening, form the subject of our pending application Serial No. 497,314, filed November 21, 1930.

While we have illustrated and described certain particular embodiments of our invention, we do not wish to be understood as intending to limit it thereto, as the same may be variously modified and altered and the invention embodied in other forms of structure without departing from the spirit of the invention.

What we regard as new, and desire to secure by Letters Patent, is:

An oil burner comprising a base member having spaced, continuous, inner and outer fuel grooves in the upper face thereof, coaxial, perforated, shells surmounting said base and co-operating with said fuel grooves to provide combustion chambers therefor, an oil supply for said grooves, a duct interconnecting said grooves adjacent said oil supply, said duct being sufficiently large to permit an igniting flame to pass from said outer groove to said inner groove, igniting wicks in said fuel grooves, and an opening in said outer shell at a point farthest from said fuel supply and having a closure means, whereby, upon starting, the wick in said outer groove may be ignited through said opening only after said wick has become fully saturated, and whereby said inner wick will become ignited through said connecting duct after the flame in the outer groove has traversed said outer groove and materially preheated the entire burner from the outer groove inwardly.

OSCAR C. SCHROEDER.
STANLEY PERRY.
